UNITED STATES PATENT OFFICE

HANS BURMEISTER, OF BERLIN, GERMANY, ASSIGNOR TO PYRENE-MINIMAX CORPORATION, A CORPORATION OF DELAWARE

APPARATUS FOR PRODUCING FOAM FOR FIRE-EXTINGUISHING PURPOSES

Application filed September 10, 1927, Serial No. 218,809, and in Germany October 26, 1926.

My invention relates to apparatus for producing foam for fire extinguishing purposes.

According to my invention the fire foam is produced by forcing powdery dry chemicals which are in conjunction with water able to form foam positively into a stream of water.

For fire extinguishing purposes in general it is already known to employ a worm conveyor to add certain chemicals to the water in order to impart an increased extinguishing capacity to the water. The standard worm conveyors employed for this purpose are, however, unsuitable for the object in view, since it is generally necessary to convey the chemicals for foam extinguishing purposes into a stream of water standing under high pressure. In a worm conveyor of the usual construction the pressure of the water would force the chemicals back again through the worm, if the operation should be a continuous one and the chemicals were not stored in a closed container. Since, however, in my present invention continuous service must be taken into account which requires a continuous supply of the chemicals, the construction of the worm must be such that the high water pressure is not able to force the chemicals back through the worm. This end in view is, for instance, attained by making the worm and its casing of gradually diminishing diameter or tapering so that the chemicals are strongly compressed by the worm at the end adjacent to the outlet from the casing. By this compression the result is attained that the resistance of the chemicals in the worm becomes so high that the water under pressure is no longer capable of forcing the chemicals back.

Another possibility of attaining the same object would, for instance, be to let the pitch of the worm become gradually less while the casing remains cylindrical. By reducing the pitch of the worm I attain the result that during the rotation of the worm and the forward feed of the chemicals the latter become more and more compressed between the turns of the worm and issue as a solid, compact mass from the mouth of the casing which likewise cannot be forced back through the worm by the service water.

In order to cause the compressed chemicals to dissolve in the current of water and to prevent them from being washed away in comparatively large lumps, a distributor, such as for example a perforated plate, is preferably provided in the service pipe through which the water carries the chemicals along in a state of fine division.

In order that the water may not flow back through the windings of the worm when the plant is stopped or chemicals are no longer fed forward, a non-return flap valve or the like is preferably provided in the service water pipe in front of the worm.

Two embodiments of my invention are illustrated in the drawing affixed hereto.

In the drawing shows

Fig. 1, a vertical longitudinal section through one apparatus embodying my invention, and

Fig. 2, a similar section through a modified apparatus.

Referring to Fig. 1 of the drawing *b* is the pipe through which flows the pressure water to which are to be added the chemicals for the generation of the foam. This tube is laterally joined by the casing *f*, in the form of a truncated cone, for housing the worm *d* also tapering towards the outlet from the casing and mounted upon the shaft *h*.

Referring to Fig. 2 of the drawing *b'* is again the water pipe and *d'* the worm mounted on the shaft *h'*. The pitch of this worm gradually decreases towards the outlet of the enveloping casing *f'* which in this case is cylindrical in accordance with the cylindrical shape of the worm.

In both designs of the apparatus a hopper *a* or *a'* is mounted upon the inlet *c* or *c'* of the casing and which serves for the introduction of the chemicals into the apparatus. The drive of the worm may be effected by a belt pulley *g* or *g'*.

In front of the outlet of the worms into the water pipe *b* or *b'* is provided a non-return flap *e* or *e'*. The pipe *b* or *b'* is fitted with a perforated plate *i* or *i'* for the purpose specified.

Various changes may be made in the apparatus without departing from the spirit

of my invention and within the appended claims.

I claim as my invention:—

1. In apparatus for producing fire foam, a worm gear for forcing the chemicals for producing the foam into a current of water under compression and subdividing means for said chemicals mounted within the pressure water pipe.
- 10 2. In apparatus for producing fire foam, a worm gear for forcing the chemicals for producing the foam into a current of water under compression and adapted to compress said chemicals prior to their discharge into said current of water and subdividing means for said chemicals mounted within the pressure water pipe.
- 20 3. In the apparatus for producing fire foam, a tapering conveyor worm and a tapering casing enveloping said worm for forcing the chemicals for producing the foam into a current of pressure water and subdividing means for said chemicals mounted within the pressure water pipe.
- 25 4. In apparatus for producing fire foam, a worm gear for forcing the chemicals for producing the foam into a current of water under compression, subdividing means for said chemicals mounted within the pressure water pipe, and a non-return member located between the casing of said worm and said pressure water pipe.
- 30 5. In apparatus for producing fire foam, a worm gear for forcing the chemicals for producing the foam into a current of water under compression and adapted to compress said chemicals prior to their discharge into said current of water, subdividing means for said chemicals mounted within the pressure water pipe, and a non-return member located between the casing of said worm and said pressure water pipe.
- 35 6. In the apparatus for producing fire foam, a tapering conveyor worm and a tapering casing enveloping said worm for forcing the chemicals for producing the foam into a current of pressure water, subdividing means for said chemicals mounted within the pressure water pipe, and a non-return member located between the casing of said worm and said pressure water pipe.
- 40 7. In the apparatus for producing fire foam, a tapering conveyor worm and a tapering casing enveloping said worm for forcing the chemicals for producing the foam into a current of pressure water, subdividing means for said chemicals mounted within the pressure water pipe, and a non-return member located between the casing of said worm and said pressure water pipe.
- 45 8. In the apparatus for producing fire foam, a tapering conveyor worm and a tapering casing enveloping said worm for forcing the chemicals for producing the foam into a current of pressure water, subdividing means for said chemicals mounted within the pressure water pipe, and a non-return member located between the casing of said worm and said pressure water pipe.
- 50 9. In the apparatus for producing fire foam, a tapering conveyor worm and a tapering casing enveloping said worm for forcing the chemicals for producing the foam into a current of pressure water, subdividing means for said chemicals mounted within the pressure water pipe, and a non-return member located between the casing of said worm and said pressure water pipe.

I affix my signature.

HANS BURMEISTER.
